CHEST OR THE LIKE

Richard M. Chapin, Charlotte, N.C., assignor to C. B. Atkin Company, Knoxville, Tenn., a corporation of Tennessee

Filed Oct. 14, 1968, Ser. No. 13,974

Term of patent 3½ years

Int. Cl. D6—01

U.S. Cl. D33—6

FIG. 1 is a front perspective view of one embodiment of a chest showing my new design;

FIG. 2 is a right side elevational view of the chest shown in FIG. 1;

FIG. 3 is a horizontal sectional view taken along line 3—3 in FIG. 1;

FIG. 4 is a fragmentary horizontal sectional view taken along line 4—4 in FIG. 1, and showing the curvature of the front of the chest;

FIG. 5 is a fragmentary vertical sectional view taken along line 5—5 in FIG. 1 and showing the curvature of the front of the chest.

The back of the chest shown is substantially plain and unornamented.

The dominant features of my design reside in those portions shown in full lines.

I claim:

The ornamental design for a chest or the like, substantially as shown and described.
